UNITED STATES PATENT OFFICE.

CHARLES HENRY PARKER, OF CODSALL, ENGLAND.

DISTILLATION OF COAL AND SIMILAR CARBONACEOUS SUBSTANCES.

Application filed January 27, 1928, Serial No. 249,966, and in Great Britain September 25, 1926.

This invention relates to apparatus for the distillation of coal and similar carbonaceous substances and especially for carrying out distillation at low or medium temperatures 5 for the production of a residue that is substantially smokeless in burning in an open grate and that has a substantial volatile content.

The invention has among its objects to 10 avoid the practical difficulties hitherto experienced in so-called low temperature distillation and to provide an apparatus that is relatively inexpensive and in which the charging and discharging are simply and 15 expeditiously performed as well as the cooling or quenching of the residue of distillation, and wherein the rate of progress through the retort is readily determinable and variable according to the character of 20 the raw material and the character of the desired carbonized product.

According to the invention the coal or other substance to be distilled is charged into receptacles advantageously of an elongated 25 or cylindrical form and these receptacles are caused to pass through the retort in which the distillation is effected by rolling upon straight inclined tracks from the charging to the discharging positions, one or a number 30 of receptacles being periodically charged while one or a number are periodically withdrawn, so that thus there is a continued progression of the receptacles through the retort.

According to the invention means are provided for charging the receptacles with the coal or other carbonaceous substance to be distilled. Means are also provided by which one or a number of receptacles may be introduced into the retort under gas tight conditions and such means comprise broadly a carrier mounted to rotate or oscillate within an enclosure or casing provided with a gap or recess. The carrier is provided of a 45 length corresponding to the length of the receptacles, the arrangement being such that part of the carrier is exposed within the gap or recess provided in the surrounding casing, so that thus the receptacle may be introduced into position on the carrier whereby the carrier may then be rotated or oscillated to cause the receptacle to pass into the retort and to fall or pass into position behind the receptacle previously introduced.

According to the invention similar means 55 are provided to withdraw one or other number of the receptacles and such means similarly comprise the use of a rotating or oscillating carrier mounted within a casing or enclosure provided with a gap or aperture 60 therein, the operation being similar to but the reverse of that of the carrier at the inlet end of the retort and being such that the last of the series of receptacles on reaching the end of the retort may pass into the corresponding recess within the carrier and on the rotation or oscillation of the carrier, the receptacle is passed outward whence it may roll or be conveyed away for the purpose 65 of cooling and discharge of its contents. 70

According to the invention, also, the receptacles for the coal or other carbonaceous substance to be distilled are of a cylindrical or other form adapted to roll or otherwise traverse the retort in the manner described 75 and are adapted to be charged with the substance to be distilled before passing into the carrier by which they are charged into the retort. Advantageously, the receptacles are of cylindrical form, open at both ends 80 and adapted to be closed by means of perforated caps or covers by which the material contained within each receptacle is retained during the passage of the receptacle through the retort. The receptacles, may, however, 85 be provided of any suitable cross-section and be adapted to be charged or discharged by any suitable means and may further be provided with annular flanges or collars or end plates of circular form by which they 90 may be adapted to travel upon the bottom of the retort itself or upon the rails provided thereon.

According to the invention, moreover, means are provided for setting the receptacles in a charging position in alignment with a charging hopper or charging cylinder into which the charge of coal or other carbonaceous substance is first passed and from which the charge may fall by gravity or be transferred by a piston or plunger into the receptacle. The receptacles may be brought into the desired position for charging by means of a run way or track and may be delivered to a turntable or like device adapted to rotate about a horizontal axis and thus to rotate the receptacle carried thereon into a position below the charging hopper or again, 100 105

the receptacles may be moved upon the runway or track into a position axially in alignment with the charging cylinder.

According to the invention means are provided by which the receptacles, after being cooled, are passed into a position where the cooled residue is discharged by means which may comprise a plunger adapted to enter the receptacle and positively to eject the charge.

According to the invention, with a view to avoid too great a length of the retort furnace or setting, the retorts are provided in connection sections of opposite inclination, and means are provided at the lower end of one section of the retort by which, on the receptacles reaching that position, they fall into the section of the retort next beneath the first and so on, the retort being advantageously formed, for example, in three such sections so that the discharging position is disposed at the opposite end or side of the setting to the charging position.

According to the invention, moreover, in such a construction of the retort, at the junctions between the adjacent sections of the retort, there may be provided rotatable carriers for the receptacles as hereinbefore described, for use in charging and discharging the receptacles into and from the retort, such carriers being advantageously operated in synchronism with the carriers at the charging and discharging ends of the retort and serving to effect the transfer of the receptacles from one section of the retort to the other.

According to the invention, moreover, the setting for the retort or retorts is provided with retort chambers in which the gases for heating the retort or retorts may be received and in which the latter may be so mounted as to permit free expansion and contraction thereof. The retort chambers may be adapted to receive the heating gases at intervals along its length from a main conduit supplied with heating gases from a producer, furnace or other source, which producer or furnace may also be provided within the setting. The introduction of heating gases into the retort chamber, however, may be so determined that a considerable volume of the heating gases necessary for heating the retort is introduced into the retort chamber at a point adjacent the upper end of the retort, the heating gases being drawn through the retort chamber to the lower end of the retort under draught to the discharge flue.

According to the invention, moreover, the volatile products of distillation are advantageously withdrawn from a point adjacent the uppermost end of the retort. They may, however, be withdrawn at any suitable point or points in the length of the retort. Thus, in a construction involving retorts in sections as hereinbefore described, the volatile prod-

ucts of distillation may be withdrawn by outlets disposed adjacent the junctions of the several sections of the retort.

According to the invention, moreover, gas such as water gas or gas prepared according to the Tully process, may be introduced into the retort advantageously adjacent the lower or discharge end so that such gas may mix with and be enriched with the gas resulting from the distillation and so that the heat of the gas so introduced may be available to assist in the carbonization of the substance being subjected to distillation.

The invention comprises the features of method and apparatus which are hereinafter described.

The invention is illustrated, by way of example, in the accompanying drawings, in which—

Figure 1 is a diagrammatic sectional elevation of a retort in three connected sections and its setting.

Figure 2 is a diagrammatic cross-sectional view of the retort and retort setting taken on the line AA of Figure 1.

Figure 3 is a detail cross-sectional view of the upper retort section and retort setting, to a larger scale, taken on the line BB of Figure 1.

Figure 4 is a detail elevation, partly in section and to an enlarged scale, of the means for connecting two sections of the retort so as to permit freedom of movement for expansion.

Figure 5 is a detail sectional elevation of the means for charging the receptacles into and sealing the retort, to an enlarged scale.

Figure 6 is a detail sectional plan view of the means represented in Figure 5, and to the same scale.

Figure 7 is a diagrammatic elevation partly in section, of the complete apparatus.

Figure 8 is a side elevation of the receptacle charging gear, and

Figure 9 is an end elevation of the receptacle charging gear.

In carrying the invention into effect, according to a construction involving a retort provided in connected sections, and as illustrated in the accompanying drawings, with a view to minimize the length of the setting, the sections 1, 2, 3 of the retort are advantageously provided one beneath the other, the section 2 being of opposite inclination to the sections 1 and 3, the lower end of each section being located immediately above and suitably connected to the upper end of the succeeding section so that the receptacles may fall or be transferred into the uppermost part of the next section of the retort.

Each section of the retort is formed of a series of cast tubular metal units *a* of substantially rectangular cross-sectional shape and flanged at each end, as at *a'*, in order to

enable the adjacent units to be secured one to the other, advantageously by means of bolts and nuts or alternatively of such securing devices as cast iron pins and cotters adapted to resist the corrosive effect of producer gas. It will be understood that the internal cross-section of the units is of a length to accommodate the length of the receptacles *b* that are provided to roll through the retorts in the manner before described. The lower internal face of each unit is advantageously provided with rails *a*² upon which the said receptacles *b* may rest. Similarly upon the lower exterior face of each unit there are advantageously provided rails or longitudinal projections *a*³ by which the units may, where possible, be supported upon rollers *c*² seated freely in suitably formed recesses in longitudinally disposed bearing plates *c*¹ fitted below the retort in the retort chamber *c*.

In order to permit of the free expansion and contraction of the retort sections, there is provided in the length of each section, and advantageously at the upper end, as indicated in Figure 1, with respect to the section 1 of the retort, an expansion collar or sleeve *d* adapted to be mounted fixedly in position and to receive slidably fitted therein the adjacent end of the retort section, the end unit *a*⁴ of which is provided with a machined surface *a*⁵ to fit within the said collar or sleeve *d*. At the junctions between the sections of retort the expansion collars or sleeves *d* may advantageously be secured to cast junction boxes *e* serving for the connection of the adjacent sections of retort.

The expansion collars or sleeves are conveniently provided to be, for a portion *d*¹ of their length, of a cross-sectional form similar to that of the units *a* of the retort sections so that, this portion being that by which the expansion collar or sleeve is mounted in position it forms a part of the retort, while for the remainder of their length, they are formed of enlarged cross-section and with slide surfaces *d*² to receive the end unit of the retort sections which are suitably formed and prepared on the exterior, as hereinbefore described, to be received therein. The expansion collars or sleeves, moreover, are advantageously provided in two or more parts meeting at *d*³ on a plane or planes parallel with the axis of the retort and suitably flanged or otherwise provided to permit them to be readily secured together.

In order that the receptacles *b* may traverse the expansion collars or sleeves *d*, the rails *a*² upon which the receptacles are carried may, immediately adjacent the extremity of the retort section, be bent or diverted laterally or reduced in cross-section to form recesses in which laterally disposed, over-

lapping portions of rail *d*⁴ formed integrally with or secured in position in the expansion collar or sleeve *d* may be disposed so as to be side by side therewith, so that a continuous rail surface is presented to the receptacles notwithstanding the expansion and contraction which takes place in the retort sections. Said portions of rail are advantageously disposed to the side of the rails *a*² against which the collars upon the receptacles, when such collars are provided, bear, and the ends of the said portions are bevelled in order that the collars may pass them readily without danger of fouling the said end in traversing the gaps which are left for expansion. Other means for maintaining a continuous rail surface may be adopted, however.

The junction boxes *e* before referred to, are mounted in position in the end walls of the retort setting *f* and may conveniently be provided as hollow rectangular casings having an end plate *e*¹ adapted to be applied upon the outer face of the retort setting and formed, opposite to such end plate with two tubular portions or sockets *e*² of cross-section corresponding to that of the units of the retort and disposed with their axes at an angle corresponding to the relative inclination of the two sections of retort to be connected. Such tubular portions or sockets, it will be understood, are provided either to be secured to the end units *a*⁶ of the adjacent section of retort or to receive an expansion collar or sleeve *d* as before referred to. In the interior such hollow casings are provided with web plates *e*³ in continuation of the rails *a*² upon which the receptacles *b* are carried in the retorts, such web plates serving to guide the receptacles from the one retort section to the other retort section. A door or manhole *e*⁴ is advantageously provided in the end plate and may carry upon it the corresponding portions of the web plates before referred to.

It will be understood that each section of retort is mounted in a corresponding retort chamber *c* which is advantageously of a cross-section corresponding to that of the retort, but conveniently provided of slightly arched form and with a longitudinal recess *c*² below the retort so that space is provided for the heating gases to pass both above and below the retort. The respective retort chambers for each section of retort communicate at the junctions between the sections, and it will be understood that the intervening portions of the walls of the retort chambers are omitted where necessary to permit of the junction of the retort sections. The bearing plates *c*¹ upon which the retort sections are supported are conveniently mounted upon the lateral edges of the longitudinal recess *c*² before referred to. Within the lower portion of the retort setting a con-

duit or conduits f^1 is or are provided for the heating gases which are supplied from a producer, furnace, or other source (not shown), and connected to such conduit or conduits there are provided upwardly directed passages f^2 from which, again, lateral passages f^3 afford communication with the retort chambers c in which are disposed the several sections of retort. Such gas passages 10 are conveniently provided in duplicate, that is to say at each side of the retort chambers. They may, however, be provided at one side only. In the setting in the positions opposite the laterally disposed passages before 15 referred to there are conveniently provided passages f^4 leading to the exterior of the retort setting and serving for the admission of air under the control of dampers or for the purpose of inspection.

20 The volatile products of distillation may be withdrawn from the retort by way of outlets provided in determined positions, the units of the retort sections at such points being formed with sockets or unions with 25 which may be connected the pipe by which the volatile products are led away in the usual manner. It is advantageous to provide a single outlet, such as a^1 , disposed near the uppermost end of the retort, but a number 30 of outlets may alternatively be provided, in which case one is advantageously provided at the upper end of the first section and the other at the opposite end of the connected first and second sections, while another 35 is advantageously provided in the position of connection of the second and third sections, while yet another may be provided adjacent the discharging position, and the gas and vapour outlet pipes may pass upwardly through the setting to a common 40 outlet pipe or main.

Such outlets may be provided where desirable upon the junction boxes before referred to. Similar means may be provided 45 for the introduction into the retort of water gas or other gas, such as that produced by the Tully process, whereby the heat of such gases may be utilized to assist in the carbonization of the substance being distilled and may be enriched with the gases evolved.

The receptacles b for the carbonaceous substance to be distilled conveniently comprise open ended cylinders of a length corresponding to that of the cross-section of 55 the retort and provided with collars or flanges b^1 adapted to maintain the receptacle in position upon the rails a^2 within the retort.

The receptacles may be provided of any 60 convenient dimensions. It is, however, preferred to provide the receptacles of a relatively small diameter; for example the receptacles may be provided of six inches diameter and four feet six inches in length, 65 and a considerable number, such as forty or

fifty for example, of such receptacles may be passing through the retort at a time. The receptacles may be conveniently provided of metal of such a thickness as to withstand the treatment to which they are subjected in use and they may be provided of a uniform thickness of, for example, one-eighth inch or one-half inch. It will, however, be understood that the invention is not limited at all to the dimensions or shape of the receptacles.

The receptacles are adapted to be closed by means of perforated discs b^2 which are conveniently of a diameter slightly less than the internal diameter of the receptacles. 80 Such discs are provided with diametrically disposed pins b^3 of rectangular cross-section, which pins are adapted to be engaged in bayonet slots b^4 formed in the extremities of the receptacles. The rectangular cross-section of the pins and the corresponding shape of the slots, it will be understood, 85 serves to prevent any rotational movement of the discs.

The means for charging the receptacles 90 into the retorts may be of any suitable construction permitting of the introduction of the receptacles singly or in a number in a substantially gas-tight manner and the same applies to the means of discharging the receptacles from the retort.

At the charging end of the retort such means conveniently comprise a cylindrical drum g formed at one or more points in the circumference with a recess g^1 or recesses in which may be nested a single receptacle b . Such drum forms the carrier before referred to and is mounted so as to be rotatable about its axis within a correspondingly formed cylindrical casing a^8 applied at the charging 105 end of the retort and provided with diametrically disposed openings by which the receptacles may pass from an inclined feed track h into the carrier g and from the carrier on to the rails a^2 at the charging end of 110 the retort. A similar carrier or rotatable drum i is provided at the discharging end of the retort but in this instance, the cylindrical casing j is provided with an annular socket j^1 for connection to the retort of such 115 form that the casing j is disposed substantially below the bottom of the retort a and so that the receptacles b passing into the carrier i may fall therein and thus the weight of the succeeding receptacles b within the 120 retort may not be applied upon the carrier. It will be understood that the carriers at the charging and discharging ends of the retort are adapted to be rotated either intermittently or continuously by suitable means in 125 such manner that the receptacles are regularly introduced into the retort and discharged therefrom, and so that the operation of the plant may thus be continuous.

For the charging of the receptacles there 130

is conveniently provided a charging hopper *k* adapted to contain and measure the quantity of coal or other carbonaceous substance to be introduced into any one receptacle. In 5 a suitable position below the charging hopper there is provided a standard *l* having at the upper end a bearing *l*¹ to receive a horizontally disposed shaft *l*² of short length having mounted upon it at one end a holder or 10 carrier *m* for the receptacles *b*. The latter comprises a frame or plate extending transversely in both directions with reference to the axis of the shaft and carrying at the outer ends laterally extending U-shaped jaws 15 *m*¹ positioned apart at a distance corresponding to the spacing of the collars *b*¹ upon the receptacles *b* by which they are maintained upon the rails *a*² in the retort.

The upper part of each jaw *m*¹ is provided with a movable clamping member *m*² adapted to engage the receptacle carried within the jaws, each clamping member being conveniently slidably carried by a pair of studs or bolts fitted to the said upper part 20 of the jaw. Each clamping member is further provided with a lug or projection on the upper face adapted to extend through an opening in the upper part of the jaw. The latter is provided on the outer side with 25 lugs *m*³ forming bearings for a spindle upon which is rotatably mounted a cam lever or like member *m*⁴ adapted in one position to engage the projection upon the clamping member *m*² and to maintain the clamping member in its position of contact with the 30 receptacle. The cam levers of the two jaws may conveniently be connected by a bar or like handle *m*⁵ by which they may be operated simultaneously, and the clamping members be mounted under spring action tending 40 to lift them from the receptacle against the action of the cam levers.

The holder or carrier *m* is adapted for a movement through 90°, the movement being 45 limited by means of a stop plate *l*³ carried on the head of the standard *l* and having an upstanding portion disposed laterally with respect to the shaft and in a position to be engaged by the lower edge of the transverse 50 body of the holder or carrier *m* when the latter is in a horizontal position, while a second stop *l*⁴ is fixedly mounted in position in the plane of rotation of the receptacle *b* seated in the holder or carrier *m* and in such 55 position that the movement through 90° brings the receptacle into a vertical position in which the stop *l*⁴ contacts with the lower jaw *m*¹ of the holder or carrier *m*. A handle *m*⁶ is conveniently provided upon the 60 body of the holder or carrier to permit it to be rotated by hand.

The holder or carrier *m* is also adapted for movement in the vertical direction and for this purpose the standard *l* upon which it is mounted may be formed as the plunger of

an hydraulic ram, or other means may be adapted for effecting a movement in the vertical direction of the standard to the extent necessary according to the distance between the inclined run-way or track *n* by which the empty receptacles are led to the charging point and the corresponding run-way or track *h* by which the charged receptacles are delivered to the retort. The inclined run-way or track *n* is extended to a position immediately adjacent the jaws *m*¹ of the holder or carrier *m* when the latter is disposed in the horizontal position.

In order that the empty receptacles *b* may be fed one at a time into the jaws *m*¹ of the holder or carrier, there are provided bearings *o* disposed laterally with respect to the inclined run-way or track, in which bearings is mounted a transverse spindle *o*¹ disposed at an elevation above the track *n*, such that the receptacles may pass below it and the said spindle carries one or more double pawls *o*² and a weighted lever *o*³ serving to maintain the pawl or pawls in such position that the foremost end thereof is depressed and engages the first of the receptacles *b*, while the rearward end is elevated above and to the rear of the said receptacle. The said lever is connected by a rod *o*⁴ of adjustable length, with a second lever or lever arms *o*⁵ pivoted below the track and extending forwardly to a position in proximity to the lower part of one of the jaws *m*¹ of the holder or carrier when the latter is in the horizontal position. The end of the said lever or one of the arms *o*⁵ is bevelled on the lower edge and the jaw *m*¹ of the holder is provided with a catch member *m*⁷ pivoted upon a horizontal spindle in suitable lugs or a recess in the jaw so formed that the catch member is adapted for a partial movement of rotation in the upward direction, but cannot rotate in the downward direction. Thus upon the upward movement of the holder or carrier *m* into the position to receive an empty receptacle *b* from the inclined track *n*, the catch member *m*⁷ will engage with the bevelled end of the lever or lever arm *o*⁵ before referred to and thus oscillate the transverse spindle *o*¹ to throw over the pawl or pawls *o*², thus releasing the first of the empty receptacles *b*, while the second of the empty receptacles is retained by the rear end of the pawl or pawls *o*² until the lever or lever arm *o*³ is out of engagement with the catch member *m*⁷. A 105 lever and pawl mechanism may advantageously be provided with respect to each of the jaws of the holder.

When the empty receptacle *b* has passed into the jaws of the holder or carrier *m*, it is engaged by the clamping members *m*² as a result of the operation of the cam levers *m*⁴ and the holder or carrier *m* is then rotated through 90° to bring the receptacle *b* into the vertical position below the charging hopper 125 130

- k. A measured quantity of the substance to be distilled is charged into the receptacle, the lower end of which has previously been closed by means of a disc b^2 . The upper end of the receptacle is then similarly closed, the holder or carrier m is again rotated into the horizontal position and the standard l is lowered to the extent necessary to bring the charged receptacle into its correct relation with respect to the inclined run-way or track h leading to the retort. The cam levers m^4 are then operated to release the clamping members m^2 and the charged receptacle is ejected from the holder or carrier m .
- 5 It will be understood that the mechanism may be adapted for electrical operation and for the purpose the movement in the vertical direction and the movement of rotation may be effected through suitable means from 20 electric motors, while the receptacle b may be retained in the jaws m^1 of the holder or carrier m by electromagnet or solenoid devices under automatic or manual control.

The clamping members may be so provided that their release serves to impel the receptacle from the seating to the said inclined run-way or track. Means may be provided whereby the operation of the clamping members, the rotation of the member carrying the receptacle, and the discharge of the hopper may be effected automatically.

35 The receptacles b which are discharged from the retort may be received upon an inclined run-way or track p by which they may be delivered to the means for discharging them, which may comprise a plunger p^1 adapted to be reciprocated through the receptacle, after the removal of the closing discs, so that the contents may be ejected 40 upon a delivery surface, such as an incline, or a travelling conveyor. The operation of the plunger may be effected automatically as the result of the arrival of the charged receptacle in the discharging position in which it 45 may be temporarily maintained by pawl devices in the manner hereinbefore described with reference to the pawls o^2 . The empty receptacles may be returned to the inclined track n leading to the charging position by a 50 traveller, elevator, or other suitable means and the closing discs may be similarly returned to the charging position.

55 On discharge from the retorts, the receptacles may pass to a cooling chamber p^2 and this cooling chamber may be arranged in any convenient position with reference to the retort, or it may be disposed immediately beneath the retort in a part of the setting through which the heating gas does not circulate, and the cooling chamber may be provided at an inclination in order that the receptacles may roll forward to the discharging position.

60 It will be understood that the cooling chamber may be so provided beneath the

last section or end of the retort that the receptacles on reaching the lower end thereof fall under gravity therein, and means may be provided at the lower end of the cooling chamber, as at p^3 , by which the discharged receptacles may be passed out from the cooling chamber in a gas-tight manner as hereinbefore described.

It will be understood that a number of the retorts may be mounted in juxtaposition in the same setting. Or again, instead of providing the retorts in sections such as hereinbefore described, the retorts may be provided in single lengths inclined to permit of the receptacles rolling down from the charging position at one side of the setting in the same line to the discharging position at the opposite side, and in such case a number of such retorts may be mounted within the same setting, one beneath the other and suitably supported by means of arches or otherwise within the setting, and so mounted that the heating gases may be conveniently accessible to them.

25 It will be understood that the retorts or retort sections may be mounted in any suitable manner within the setting so that the heating gases are accessible to the retorts or retort sections for the application of heat external to the retorts, and for this purpose 90 any suitable form of setting may be employed, but in addition to applying heat externally to the retorts hot gas may be circulated through the retorts.

30 The means provided for charging the receptacles with the coal or other carbonaceous substance to be distilled and the means employed for discharging the residue from the receptacles may be set in any convenient position with reference to the retort without 100 departing from the invention.

35 We are aware that it is known to secure the continuous progression of cylindrical receptacles containing ore through an inclined roasting furnace by the use of vertically sliding doors closing the furnace.

40 I claim:

45 1. Apparatus for the distillation of coal and similar carbonaceous material, comprising a retort formed in connected tubular sections defining a continuous descending path, a setting in which certain of said sections are fixedly supported and the other sections are slidably supported, said setting having passages therein for the distribution 115 of heating gases about said retort, the fixed sections of said retort being telescopically connected to said other sections to permit relative endwise movement under expansion, substantially cylindrical receptacles in which the carbonaceous material is charged adapted to roll in said retort sections, means in said retort sections for guiding said receptacles, and means for sealing the ends of said retort. 120

50 2. Apparatus for the distillation of coal and similar carbonaceous material, comprising a retort formed in connected tubular sections defining a continuous descending path, a setting in which certain of said sections are fixedly supported and the other sections are slidably supported, said setting having passages therein for the distribution 125 of heating gases about said retort, the fixed sections of said retort being telescopically connected to said other sections to permit relative endwise movement under expansion, substantially cylindrical receptacles in which the carbonaceous material is charged adapted to roll in said retort sections, means in said retort sections for guiding said receptacles, and means for sealing the ends of said retort. 130

2. Apparatus for the distillation of coal and similar carbonaceous material, comprising a tubular retort defining a continuous descending path from a charging position 5 to a discharging position, a setting in which said retort is supported and having passages for the distribution of heating gases about said retort, substantially cylindrical receptacles in which the carbonaceous material 10 is charged adapted to roll from the charging position to the discharging position, and

means for sealing the retort adjacent its ends comprising casings and substantially cylindrical carriers rotatably mounted therein, each of the said casings having an opening to receive one of said receptacles and adapted in one position to register with an opening outside said retort and in another position to register with the inside of said retort. 15

CHARLES HENRY PARKER.
